UNITED STATES PATENT OFFICE

JAMES PAUL GRIFFITHS, OF DURBAN, NATAL, SOUTH AFRICA, AND WILLIAM STREET-WILSON, DECEASED, LATE OF DURBAN, NATAL, SOUTH AFRICA, BY EDMUND M. LAUGHTON AND EDMUND H. CLEMMANS, EXECUTORS

RAIL CHAIR

Application filed October 26, 1928, Serial No. 315,336, and in Union of South Africa November 10, 1927.

This invention relates to rail chairs primarily intended for railway rails. It relates more particularly to rail chairs of the kind including a cast steel or other metal bed plate or base plate having two raised lugs or upstanding projections adapted to be disposed or arranged one on either side of the flange or base portion of the rail.

The object of the present invention is to construct a rail chair of the type above referred to which will serve effectively to retain the rail in position and prevent both the creeping of the rail in a horizontal direction and any vertical lift.

In carrying out the invention in one form we provide a base portion or bed plate which as usual is provided with holes through which pass coach or other screws for fastening the base or bed plate to the sleeper or its equivalent. This base or bed plate, which may be made of cast steel, is constructed with two lugs or upstanding projections, one extending considerably higher than the other, and a flat part between such projections upon which the rail is arranged.

The higher or larger lug or projection is rabbeted, recessed, or hollowed out in its lower portion next the flat central portion of the chair, and said rabbet or recess may be tapered or made gradually shallower from one side of the lug to the other, and tapered or made gradually narrower from top to bottom from one side of the lug to the other.

The other and smaller lug or projecting portion is preferably also rabbeted, recessed or hollowed out, so that the one side of the base of the rail will lie in such rabbet or recess.

The other side portion of the base of the rail lies opposite the rabbet in the first mentioned and larger lug or projection, and is held in position by a key or wedge which is preferably formed with a double taper.

Between the web of the rail and the face of the higher lug or projection a wedge-shaped block or cushion of wood or other suitable relatively soft material is inserted, 50 the face of the lug or projection being suit-

ably inclined so that the wedge bears against it along its whole length.

The key or wedge which serves for keeping the rail in position on the chair is rabbeted or provided with a longitudinal recess along its bottom edge on the side adjacent the rail, so that the edge of the base of the rail lies in said rabbet. It is also rabbeted or provided with a longitudinal recess along its diagonally opposite edge, and through the opening provided by said rabbet or recess passes a bolt preferably provided with a head portion at right angles thereto. The head portion of the bolt is placed against the side of the lug or projection nearest the smaller end of the wedge, and a washer and, say, a wing nut are placed upon the other end of the bolt. The washer bears against the larger end of the wedge, and projects for some distance beyond the same. On tightening the nut the washer acts to force the wedge into the recess formed in the lug or projection which acts tightly to fix the rail on the chair between the wedge and the lug or projection formed on the other side of the chair. This washer also serves to limit the longitudinal movement of the wooden block or cushion.

The larger or higher lug or projection is preferably cast or formed on the side opposite the inner flange of the rail, if the chair be used on curves or gradients.

If desired, a longitudinal recess may be formed in the higher lug or projection, and a bolt be inserted therein having a head at right angles thereto and provided with a nut and washer, which might serve positively to retain the wooden block or cushion in position.

In a modified form of the invention suitable more particularly for double check rails, one of the higher lugs or projections and the wedge and wooden block or cushion could be provided at either side of the chair, and a similar lug or projection be provided centrally longitudinally of the chair between the rails, and be rabbeted or hollowed at both sides to take the opposite edges of the bases of the two rails.

In a further modified form of the in-

vention, suitable more particularly for use on substantially level tracks, the high lugs or projections could be dispensed with, and two smaller lugs or projections be provided 5 one on either side of the chair with the rail resting on the chair between them. In this case one of the lugs or projections could be hollowed out or rabbeted to take the preferably double tapered key or wedge, and 10 the other could be hollowed out or rabbeted to take the edge of the base of the rail. In this form of the invention the wedge would be provided with a screw threaded extension or a thumb screw, or have a bolt passing longitudinally therethrough. A washer on the bolt or screw threaded extension would rest against the side of the chair preferably engaging therewith above and 15 below the rabbet, and the wedge could be tightened up or drawn into position to secure the rail by tightening up the nut against the washer.

Obviously in the case of a single rail, wedges and/or wooden blocks or cushions 20 could be employed as desired at both sides of the rail and the chair be constructed accordingly.

The wooden cushion or wedge serves to support the rail through the web, and acts 25 to prevent or minimize knocking or concussion due to lateral, downward or upward pressure, so promoting smooth running of the vehicles on the rails.

The bolt, thumb-screw, or equivalent, acts 30 to secure both the key and the wooden cushion or wedge in position, locking them effectively and preventing the possibility of 35 their coming out of position.

Fig. 1 is a vertical elevation of the flat 40 foot rail chair specially designed for curves and gradients.

Fig. 2 is a plan view of Fig. 1 showing rail web in section.

Fig. 3 is a vertical elevation of a similar 45 type as Fig. 1, but is designed for the double check rail.

Fig. 4 is a vertical elevation of a modified type for use on levels.

Fig. 5 is a plan view of Fig. 4 showing rail 50 web in section.

As shown in Figures 1 and 2 a cast base plate *a* is secured to the sleeper (not shown) by means of the ordinary coach screws *i*. This base plate which is cast has the two lugs 55 *b* and *c* cast on it. *b* is carried up to support the wooden cushion *h*, and is hollowed out at the base to receive the double rabbeted and double tapered key *d*, which is inserted 60 with the thumb and finger and pushed home. The wooden cushion *h* is then put in place, and the bolt *e* is inserted, the washer and nut *f* adjusted which effectively prevents the possibility of the key *d* or the cushion *h* from 65 withdrawing. The lug *c* is cast on the inner

side of the base plate, and is for gripping the inner flange of the rails.

The other side of the web *r* may be similarly gripped or alternatively the construction shown may be employed.

Figure 3 is a similarly cast chair but with the two outer lugs *b* carried up as shown, for use with a check rail. The cast piece *l* holds the flanges of both rails.

The chair of Figures 4 and 5 is also similarly constructed but is intended for use on the level, for yards, sidings, etc., the lug *b* being cast similarly to that of *c* but hollowed out at the base to receive the double tapered and rabbeted key which is effectively secured with a screw on the end at *f* with washer and nut to prevent the possibility of its withdrawal.

It will be noted that the thumb screw or bolt and cushion are especially new and novel in this treatment and use, and are special features of this patent.

What we claim is:

1. A chair for railway rails or the like comprising a bed plate having two lugs so located as to permit the placing of a rail between them, one of said lugs adapted to engage one lateral edge of the rail flange, the other lug having within it a keyway which is double tapered toward one end thereof, a wedge-shaped key which is double tapered in complementary relation to the keyway, said key being adapted to engage within said keyway to coact therewith and with the other lateral edge of the rail flange to anchor the rail against both the first lug and the bed plate.

2. A chair for railway rails or the like comprising a bed plate having two lugs so located as to permit the lowering of a rail into place between them, one of said lugs adapted to engage one lateral edge of the rail flange, the other lug having along its inner face a rabbet, which is so shaped that both the width and height of said rabbet taper toward one end thereof; a key for cooperative engagement with the tapered walls of the rabbet and the adjacent lateral edge of the rail flange and means cooperating with the key and the last-mentioned lug to draw the key into the rabbet to anchor the rail to the chair.

3. A chair for railway rails or the like comprising a bed plate having two lugs so located as to permit the lowering of a rail between them, one of said lugs adapted to engage one side of the rail flange, the other lug having a substantially vertical inner face inclined with respect to the rail web and also having at its base a keyway which is double tapered toward one end thereof; a wedge-shaped key which is double tapered in complementary relation to the keyway, the tapered sides of said key and keyway being adapted to coact with each other; a wedge

of cushioning material disposed between the rail web and said latter lug, said wedge being tapered in the same direction as said key and complementing and coacting with the inclined face of said lug; and means adapted to force and securely hold said key into the keyway and said wedge into wedging position, whereby to anchor the rail.

4. A chair for railway rails or the like comprising a bed plate having two lugs so located as to permit the placing of a rail between them, one of said lugs adapted to engage one side of the rail flange, the other lug having a substantially vertical inner face inclined with respect to the rail web and also having at its base a keyway which is double tapered toward one end thereof; a wedge-shaped key which has a rabbet along its upper inner edge, and is double tapered in complementary relation to the keyway, a wedge of cushioning material disposed between the rail web and said latter lug, said wedge being tapered in the same direction as said key and complementing and coacting with the inclined face of said lug; and a bolt, nut and washer, the bolt extending through said rabbet, the head of the bolt seating upon one side of said latter lug, the other end of the bolt having thereon the nut and washer, said washer seating upon the larger ends of both the key and the wedge, whereby when the nut is taken up on the bolt, both the key and the wedge are forced and held into locking position and the rail is anchored against both the first lug and the bed plate.

Signed at Durban in the Natal Province of the Union of South Africa, on this the 15th day of Sept., 1928.
